BOBBY PIN HOLDER AND SPREADER

Henry M. Bohmholdt, Niagara Falls, N. Y.

Application November 30, 1951, Serial No. 259,246

2 Claims. (Cl. 132—1)

1 This invention relates to an improved holder and spreader for bobby pins for use by a hair-dresser, and more particularly to a device of this kind which is adapted to be held by a customer and which can hold a number of bobby pins in spaced apart relationship and which will enable opening or spreading bobby pins as they are removed from the device.

It is among the objects of the invention to provide an improved bobby pin holder and spreader of the above indicated character which can be in the form of a flat and substantially rigid bar which can be conveniently held by a customer for use by a hairdresser, and will hold a sufficient number of bobby pins to complete a hair-curling operation; which can be loaded at the leisure or convenience of the operator and stored in loaded condition until required for use; which will receive bobby pins in different positions thereon, so that the bobby pins can be removed from the holder and simultaneously spread by different movements of the pins relative to the holder as may be found most convenient by different operators; which maintains the bobby pins sufficiently spaced apart so that any one of the pins can be manually removed from the holder without disturbing adjacent pins; and which is simple and durable in construction, economical to manufacture, easy to use and neat and attractive in appearance.

Other objects and advantages will become apparent from a consideration of the following description and the appended claims in conjunction with the accompanying drawing, wherein:

Figure 1 is a perspective view of a bobby pin holder and spreader illustrative of the invention;

Figure 2 is a transverse cross-sectional view on the line 2—2 of Figure 1; and

Figure 3 is a transverse cross-sectional view on the line 3—3 of Figure 1.

With continued reference to the drawing, the illustrated bobby pin holder and spreader comprises an elongated, flat bar 10 preferably approximately 18 inches long, one-quarter of an inch thick, and 1½ inches in width. The bar has straight and substantially parallel side edges 11 and 12 and semicircularly rounded ends 13 and 14, and is provided near each end with an aperture, as indicated at 15 and 16, approximately one-quarter of an inch in diameter and concentric with the curvature of the corresponding semicircularly curved ends of the bar. The bar also has a series of holes 17 centered along a straight line extending longitudinally of the bar between the side edges 11 and 12, but located

2 somewhat nearer the edge 11 than the edge 12. The holes 17 are spaced apart approximately one inch and have a diameter of approximately 7/16 of an inch, so that each hole can receive one leg of a conventional bobby pin, as shown in Figure 1.

The bar 10 may be formed of any suitable, substantially rigid material, such as wood, metal, synthetic resin plastic or hard rubber.

In applying a bobby pin to the holder, its smooth or straight leg 19 is to be inserted through one of the holes 17, and the ridged or corrugated leg 20 is engaged over the near straight edge 11 of the bar so that the bobby pin is held on the bar and maintained in partly spread condition. In removing a bobby pin so disposed on the bar 10 the operator grasps the bobby pin at a point between the closed end of the bobby pin and the bar 10 between thumb and forefinger and applies sufficient pressure to the sides of the bobby pin to hold it in its partly opened or partly spread condition, and then exerts sufficient pull on the bobby pin to pull the smooth leg 19 out of the hole 17 involved and pull the corrugated leg 20 off of the near edge 11 of the bar 10, as shown in Figure 2.

For maximum spreading of a bobby pin 18, the ridged or corrugated leg 20 is inserted through one of the holes 17 from one side of the bar 10, and the free end of the smooth leg 19 is rested 30 against the same side of the bar 10, with the free end of the smooth leg 19 positioned close to the far edge 12 of the bar 10. In removing a bobby pin so positioned and maintaining it in spread condition, the operator grasps the bobby pin at a point between the closed end of the bobby pin and the bar 10 between thumb and forefinger, as shown in Figure 3, and then first pulls the closed end of the bobby pin downwardly, so as to force the smooth leg 19 under the far side edge 12 of the bar 10 and thereby spread the bobby pin a materially greater amount than is obtainable by the arrangement shown in Figure 2. Then, while holding the bobby pin in spread condition between thumb and forefinger, the operator exerts a pull on the bobby pin in a direction away from the bar 10, so that the corrugated leg 20 of the bobby pin is drawn out of the hole 17 in the bar 10, the spread condition of the bobby pin being maintained by the thumb and forefinger.

By spacing the holes approximately one inch apart, the bobby pins are supported on the bar at sufficient distances apart so that any pin can be manually removed from the bar without disturbing adjacent bobby pins, and, by positioning the row of holes 17 nearer one edge of the bar

3

10 than the other, the bobby pins can be either partly or fully spread as they are removed from the bar.

The bar 10 can be easily loaded with bobby pins during the leisure or convenience of the operator, and when loaded, may be supported by hanging it from a nail or peg extending through one of the apertures 15 or 16 in the bar until the loaded holder is required for use.

The end portions of the bar 10 in which the holes 15 and 16 are provided constitute handle portions, one at each end of the bar, and it is contemplated that the bar will be held by a customer with each hand of the customer grasping a handle portion at the corresponding ends of the bar 10, so that the operator can quickly and easily remove bobby pins from the bar and insert them directly into the hair of the customer without loss of time.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A holder and spreader for bobby pins each having a straight leg and a corrugated leg connected together at one end by a bight, comprising a flat bar having straight side edges and having one end portion thereof serving as a handle, 35

said bar being provided with a plurality of holes arranged in longitudinal spaced relation therealong intermediate said one end portion and the other end thereof, each of said holes being nearer to one than the other of said side edges and being adapted to receive either the straight leg or corrugated leg of said pin while the other leg is deflected outwardly by frictional contact with either said one side edge of said plate or with the adjacent face of said plate.

2. A holder and spreader for bobby pins each having a straight leg and a corrugated leg connected together at one end by a bight, comprising a flat bar having straight side edges and having each end portion thereof serving as a handle, said bar being provided with a row of holes arranged in longitudinal aligned spaced relation therealong intermediate said end portions, each of said holes being nearer to one than the other of said side edges and being adapted to receive either the straight leg or corrugated leg of said pin while the other leg is deflected outwardly by frictional contact with either said one side edge of said plate or with the adjacent face of said plate.
